DRUMMER'S PRACTICE DEVICE

Henry Adler, Brooklyn, N. Y.

Application April 26, 1946, Serial No. 665,092

16 Claims (Cl. 84—411)

1

This invention relates to percussion and practice devices and more particularly to practice devices for drummers simulating the effect of a drum on the drum sticks, while giving very little noise, though it is noted that in some of the claims the invention is not limited to practice devices nor even to percussion devices.

Objects of the invention are to provide an improved device or apparatus of this kind which produces very little noise, but which enables the drummer to judge the effect of his strokes on a real full-sized drum.

Other objects of the invention are to provide an improved device of this kind which is adjustable to give different sound effects and which will yieldably hold the different adjustments.

Additional objects of the invention are to effect simplicity and efficiency in such devices and to provide an extremely simple portable device of this kind which is durable, and reliable in operation, and economical to manufacture.

Still other objects of the invention will appear as the description proceeds; and while herein details of the invention are described in the specification and some of the claims, the invention as described in the broader claims is not limited to these, and many and various changes may be made without departing from the scope of the invention as claimed in the broader claims.

The inventive features for the accomplishment of these and other objects are shown herein in connection with a drummer's practice device which briefly stated, includes a box having a base, front and back side walls thereon, and a top wall having a central thin percussion portion over which is disposed a resilient pad secured on the top wall. Hinged control doors are provided for the ends of the box and a rotary shaft supported transversely of the box and having an exterior operating knob carries levers fast on the shaft linked to the doors for adjusting the latter by manual operation of said knob. Means are provided for yieldably holding the shaft and consequently the doors in adjusted position.

This practice device is particularly adapted for use by students of drums and percussion type instruments, and is not intended principally for use in orchestras and bands, but is for enabling students to practice without causing objectionable noise and disturbance. However, with the resilient pad made thinner or removed the device could be used for special effects intended to be heard by audiences. The device is designed so as to allow use in various degrees of sound, tone and volume.

This device eliminates the inconvenience of a large and noisy full-sized instrument and permits students to practice effectively and with full force without annoying other persons.

A further object of this invention is to provide

2

an improved practice device which although emitting sounds of greatly reduced volume, still allows the student to imagine, or visualize, and comprehend the varying effects of his efforts. This is accomplished through the use of the enclosed resonance chamber which can be adjusted by means of the control doors. When these doors are opened a certain pitch, tone or volume is produced. As the doors are closed the tone or sound varies in proportion to the angle or degree of closing said doors. This enables the student to practice volume control and constitutes a remarkable advantage over the ordinarily used practice devices. It will also result in an improvement in the abilities of those practicing to perform on the regular sized instruments.

A further object of the invention is the provision of a practice pad wherein the volume control doors are lined with felt so as to produce a muffed sound effect when desired.

A still further object is the provision of the practice pad or slab on the top wall to cause the drumsticks to spring back and vibrate, reverberate or roll in the same manner as they would on the surface of a regular full-sized drum.

In the accompanying drawing showing, by way of example, one of many possible embodiments of the invention,

Fig. 1 is a perspective view of the practice device; and

Figs. 2 and 3 are sectional views taken respectively on the lines 2—2 and 3—3 of Fig. 1 looking in the direction of the arrows of said lines.

My improved drummer's practice device comprises a wooden box having a thick elongated rectangular base 10, longitudinal front and back side walls 11, 12 mounted on the base within the margins thereof and having aligned large-diameter and small-diameter bearing bores 13, 14 slightly above the center of the walls. A top wall 15 secured on said side walls and cooperating with the walls and base to provide an open-ended resonant sound chamber has a central circular cut-out 16 and a communicating longitudinal clearance space 17 in its inner face, said cut-out 16 providing a central thin percussion portion 18 in the top.

A resilient practice pad 20 of rubber or other resilient material cemented or otherwise secured on the intramarginal part of the top face of the top over said thin portion 18 is adapted to be struck by the drumsticks and to cause the drumsticks to spring back and reverberate to simulate the action and reduced sound from a full-sized drum.

Thick wooden doors 21 for the ends of the box may each have a felt lining 21a, if desired, and are each hinged by hinges 22 at the outer edge of its lower edge face to the top face of the margin of

the base 10 in position to close the chamber completely when the doors are upright, and adapted to be adjustably opened as will be explained, to modify the sound from the chamber.

Means for controlling the adjustment of said doors will now be described. A shaft 23, 24 supported in said bearing openings comprises a large diameter portion 23 disposed in the large bearing bore 13, a reduced diameter portion 24 disposed in the small bearing bore 14, an intermediate shoulder 25 between the portions, and an operating knob 26 at the exterior of the chamber. A cross-pin secured through the mid-part of the shaft between the shoulder and front wall projects equal distances to form levers 28 provided with transverse apertures in the respective outer ends receiving the turned inner ends 30 of links 31 having turned outer ends 32 received in screw eyes 33 secured in the upper inner margins of the doors, whereby manual rotation of the knob 26 may simultaneously open or close said doors. The cut-out 16 and space 17 afford clearance for a lever 28 and associated link.

An arcuate series of round headed studs 35 in the inner face of the front wall 11 adjacent to the knob forms a series of detent projections coaxial with the shaft; and a detent pin 36 secured transversely in said shaft adjacent to the back wall is slidable on and engageable between adjacent projections, to hold the pin and shaft in any one of four or more adjusted positions depending upon the number of projections. A pair of washers 36, 37 are disposed on said reduced diameter portion 24 against the back wall 12 and said shoulder 25; and a helical compression spring 38 on the reduced diameter portion is compressed between said washers, whereby said detent pin 36 is yieldably pressed between the projections 35 and is adapted yieldably to hold the shaft and doors in adjusted position and to cam over said projections, when the knob is turned, to allow adjustment of the shaft and consequently the doors, to adjust the tone and volume of the sound chamber.

In operation the pad is beat upon by the drumsticks in the same manner as the real drum is struck; and the sound volume is controlled by adjustably opening and closing the doors 21. To adjust the doors, the knob 26 is pushed inwardly against the action of the spring 38, to disengage the pin 36 from the projections 35, and while so pressed the knob is rotated to the left or right to open or close the doors the desired amount. Then the knob is released, allowing the detent pin to engage between the projections to hold the parts in adjusted position.

If it is desired to produce a muffled sound effect, the felt lining 21a may be provided on the doors; but it is not necessary to provide the linings if the muffled effect is not desired, and without the felt lining a slightly different muffled effect may be obtained by nearly closing the doors.

The pad 20 may be made softer or thicker to give less noise, or harder or thinner to give more noise. Provision of the felt lining 21a gives less noise; and the noise is increased as the doors are progressively opened.

My improved percussion practice device, to simulate drum effects, with little noise comprises a thick wooden box having thick doors and side walls thereon and a thick top wall having a thin portion on which the resilient pad is secured to simulate drum effects with little noise when struck, the doors being equally open in any of several adjusted positions, to cause the device

to give even tones, which is very important to a musician accustomed to the recognition of tone quality. By the adjustment it is possible to simulate the sound of different drums when adjusted to the required positions.

The resilient pad is secured on the top wall and extends over and beyond all margins of the circular cut-out and said thin portion; and when the pad is struck near and inwardly remote from said margins it simulates drum sounds when the drum is struck remote from and near the rim respectively.

The thin percussion portion 18 having a thin pad 20 or without the pad forms a percussion portion and is adapted when struck by a drumstick to give special sound effects which can be heard by audiences. The pad 20 secured over the thin portion 18 as shown forms a percussion portion adapted, when struck by the drumstick in the same manner as a real drum is struck, to emit reduced volume sounds simulating the sounds of a real drum and to enable the drummer to judge the effect of his strokes on a real full-size drum.

The invention claimed is:

1. A drum simulating percussion device comprising a box having opposite open ends, a substantially unobstructed interior and a thin percussion portion in its top wall, and a resilient pad secured on the top wall over said thin portion.

2. A drum simulating percussion device comprising a box having opposite open ends, a substantially unobstructed interior and a thin percussion portion in its top wall; doors for said ends, and felt linings for said doors.

3. A percussion device comprising a box having a closed base, front and back side walls thereon, and a top wall; a resilient pad secured on the top wall; doors for the ends of the box; a rotary shaft supported transversely of the box and having an exterior operating knob; levers on the shaft linked to the doors for adjusting the latter; and means for yieldably holding the shaft and consequently the doors in adjusted position.

4. In combination, a wooden box comprising a base, front and back side walls thereon, and a top wall secured on said side walls to provide a sound chamber and having a central thin portion; a resilient pad secured on the top wall over said thin portion; doors for the ends of the box hinged at the lower part to the base; a rotary shaft supported in said side walls transversely of the box and having an exterior operating knob; a cross-pin secured through the shaft to form opposite levers; links pivotally connected to the outer ends of the levers and the upper inner margin of the doors; an arcuate series of rounded detent projections on the inner face of the front wall coaxial with the shaft; a detent pin secured transversely in said shaft and slidable on and engageable between the projections; and spring means yieldably urging the shaft toward the front wall, and the detent pin to and between the projections.

5. A percussion device comprising a wall thereon having a thin portion; a resilient practice pad of rubber cemented on the intramarginal part of the outer face of the wall over said thin portion adapted when struck with drumsticks to cause the drumsticks to spring back and vibrate to simulate the action and sound from a full-sized drum.

6. In combination, a wooden box comprising an

elongated thick rectangular base, longitudinal front and back side walls mounted on the base within the margins thereof; a top wall secured on said side walls and cooperating with the walls and base to provide an open-ended sound chamber; said top wall having a central circular cut-out, said cut-out providing a central thin portion in the top; and a practice pad of resilient material secured on the intramarginal part of the top face of the top over said thin portion and adapted when struck by drumsticks to cause the drumsticks to spring back and reverberate to simulate the action and sound from a full-sized drum.

7. A practice device comprising an open-ended box having a base, side walls, a top wall and percussion portion in its top wall; thick wooden doors for the ends of the box each hinged at the outer edge of its lower edge face to the top face of the margin of the base in position to close the chamber completely when the doors are upright, and adapted to be adjustably opened to modify the sound from the chamber; and means for controlling the adjustment of said doors.

8. A percussion device comprising an open-ended box having a thin portion in its top wall; doors for the ends adapted to be held in adjusted position; said doors having linings of sound muffling material.

9. In combination, an open-ended box having a base, front and back walls, a top wall and a percussion portion in its top wall; said front and back walls having aligned large-diameter and small-diameter bearing bores slightly above the center of the walls respectively; a shaft supported in said bearing openings and comprising a large diameter portion disposed in the large bearing bore, a reduced diameter portion disposed in the small bore, an intermediate shoulder between the portions, and an operating knob at the exterior of the chamber; means connecting the shaft and doors for operating the doors; an arcuate series of round headed studs in the inner face of the front wall adjacent to the knob and forming a series of detent projections coaxial with the shaft; a detent pin secured transversely in said shaft adjacent to the back wall and slidably on and engageable between a pair of washers on said reduced diameter portion against the adjacent side wall and said shoulder; and a helical spring compressed between said washers whereby said detent pin is yieldably pressed between the projections.

10. In combination, an open-ended box having side walls, a top wall having a percussion portion, and doors for the open ends; a shaft across the box rotatably mounted in the side walls having exterior operating means; an arcuate series of rounded detent projections on the inner face of the back wall coaxial with the shaft; and a detent pin secured transversely in said shaft and slidable on and engageable between the projections; and spring means yieldably urging the shaft toward the front wall, and the detent pin to the projections.

11. In combination, a box having a base, front and back side walls thereon, and a top wall; a resilient pad secured on the top wall; doors for the ends of the box; a rotary shaft supported transversely of the box and having an exterior operating knob; levers on the shaft linked to the doors for adjusting the latter; an arcuate series of round headed studs in the inner face of the front wall adjacent to the knob and forming a series of detent projections coaxial with the

shaft; and a detent pin secured transversely in said shaft adjacent to the back wall and slidable on and yieldably engageable between adjacent projections.

12. A percussion practice device adapted to simulate drum effects with little noise, comprising a wooden box having a substantially unobstructed interior, opposite open ends, closed base, closed front and back side walls thereon, closed thick top wall having substantially at the mid-part of the inner face a thin portion; a resilient pad secured on the top wall over said thin portion and adapted when struck by a drum stick to give an audible sound to simulate drum effects.

13. A percussion practice device adapted to produce sound effects, comprising a wooden box having a substantially unobstructed interior, opposite open ends, closed base, closed front and back side walls thereon, closed thick top wall having substantially at the mid-part a thin portion adapted when struck by a drum stick to give an audible sound effect; the opposite open ends effecting even distribution of the sound; doors for the opposite ends of the box; and means for holding the doors open in any of several adjusted positions, to cause the device to give different sounds.

14. A percussion practice device adapted to produce sound effects with little noise, comprising a wooden box having opposite open ends, closed base, closed front and back side walls thereon, closed thick top wall having substantially at the mid-part a thin portion; a resilient pad secured on the top wall over said thin portion and adapted when struck by a drum stick to give an audible sound effect; the opposite open ends effecting even distribution of the sound; doors for the opposite ends of the box; means for adjustably opening the doors equal amounts; and means for holding the doors equally open in any of several adjusted positions, to cause the device to give even tone, and to give the different sound effects.

15. A percussion practice device adapted to simulate drum effects with little noise, comprising a wooden box having opposite open ends, closed base, closed front and back side walls thereon, closed thick top wall having a circular cut-out substantially in the mid-part of the inner face forming a thin portion; and a resilient pad secured on the top wall and extending over and beyond all margins of said thin portion and adapted when struck inwardly remote from said margin to simulate, with little noise, drum sounds when the drum is struck remote from the rim of the drum, and adapted when struck near said margin to simulate drum sounds when the drum is struck near the rim of the drum.

16. A percussion practice device adapted to simulate drum effects with little noise, comprising a wooden box having a substantially unobstructed interior, opposite open ends, closed base, closed front and back side walls thereon, closed thick top wall having a circular cut-out substantially in the mid-part of the inner face forming a thin portion adapted when struck by a drum stick to give an audible sound effect; a resilient pad secured on the top wall and extending over and beyond all margins of said thin portion and adapted when struck inwardly remote from said margin to simulate, with little noise, drum sounds when the drum is struck remote from the rim of the drum, and adapted when struck near said margin to simulate drum sounds when the drum is struck near the rim of the drum; the opposite

open ends effecting even distribution of the sound; doors for the opposite ends of the box; means for progressively adjustably opening the doors equal amounts; and means for yieldably holding the doors equally open in any one of several adjusted positions, to cause the device to give even tone, and to simulate the sound of different drums corresponding to different degrees of adjustment of the doors.
